United States Patent Office.

JAMES SUTHERLAND, OF MORRIS, ILLINOIS.

Letters Patent No. 74,253, dated February 11, 1868.

IMPROVEMENT IN WAGON FOR LOADING LOGS, STONE, AND HAY.

The Schedule referred to in these Letters Patent and making part of the same.

TO ALL WHOM IT MAY CONCERN:

Be it known that I, JAMES SUTHERLAND, of Morris, in the county of Grundy, and State of Illinois, have invented a new and improved Combined Log, Stone, and Hay-Loader; and I do hereby declare that the following is a full, clear, and exact description of the construction and operation of the same, reference being had to the accompanying drawings making a part of this specification, in which the figure in the drawings represents a side elevation.

The nature of my invention consists in the arrangement of a stationary grooved upright, sliding elongated ratchet, lever and pawls, swinging-lever and grappling-iron, for loading or unloading logs, stones, hay, or any other article on or from a wagon.

To enable any one skilled in the art to make and use my invention, I will proceed to describe its construction and operation.

A is the wagon, B the upright attached to rear end of the wagon. It is provided with a groove, in which the back edge of the ratchet C is placed, the groove being sufficiently loose for it to slide freely up and down therein, and secured thereto by plates, *a a*, bent around and over the front edge of the ratchet, and fastened into the upright. D is a pawl, for supporting and holding the ratchet vertically. E is a lever, with a pawl, *b*, at its end, and having its fulcrum, F, attached to the top of the upright. G is the swinging-lever, provided with a socket and with a pivot, *c*, of the ratchet (which is constructed on the top of it) fitting therein. H is the grappling-iron, with double prongs on one side and single on the other. It is secured by chain and ring to the hook of the lever. The swinging-lever, grappling-iron, and ratchet can easily be taken apart and removed from the wagon at any time.

Operation: The lever G, being swung around to one side of the wagon, the grappling-iron H is lowered and fastened to the article to be raised, which is done by bearing down on the other end of the lever, and when the article has been raised high enough the lever is swung back, and the same laid on the wagon, and the iron disengaged therefrom. If it is found that the ratchet C is too high or too low for a convenient handling of the lever G in depositing the article, or when beginning to raise it on the wagon, by releasing the pawl D from the teeth of the ratchet, and taking hold of the lever E, and raising it up or pressing it down, the ratchet may be lowered or raised to the height desired. In either case the pawl D is placed back again to hold the ratchet.

Having thus fully described my invention, what I claim therein as new, and desire to secure by Letters Patent, is—

The construction and arrangement of the stationary grooved upright B, sliding elongated ratchet C, lever E, and pawls *b* and D, swinging-lever G, and grappling-iron H, in combination with a wagon, substantially in the manner and for the purpose as herein set forth.

JAMES SUTHERLAND.
